FLUID DISTRIBUTOR

Doyle C. Warren, Monrovia, Calif., assignor to
 Chiksan Company, Brea, Calif., a corporation
 of California

Application July 26, 1948, Serial No. 40,750

2 Claims. (Cl. 137—21)

1

This invention is concerned with a fluid distributor and it is a general object of the invention to provide a simple, practical, and easily operated structure that can be used to advantage in the handling or distribution of fluids.

There are numerous situations where fluids are delivered from a supply, as for instance by means of a supply pipe, and require delivery through a nozzle or spout at various points remote from the said supply pipe. An example of such a situation is in the case of an oil or gasoline depot where the liquid to be handled is supplied through a pipe and is to be delivered into containers or tanks on either trucks or trailers. In such a case the tanks vary as to the height of their filling openings and the openings vary in distance from the supply pipe, making it advantageous to employ a delivery spout coupled to the pipe so that it is universally movable.

Structures heretofore provided for the type of mentioned work have been more or less complicated and, consequently, cumbersome, and unless they are accurately counterbalanced they are difficult and hazardous to operate.

It is a general object of this invention to provide a structure applicable to a supply line or fluid delivering pipe and involving an arm universally coupled to the pipe and a spout universally coupled to the arm, the entire structure being counterbalanced so that it is simple, convenient, and easy to operate.

Another object of this invention is to provide apparatus of the general character referred to wherein the parts are of simple form and are so arranged that the structure is compact and most convenient to use. In the structure provided by the present invention the counterbalance employed in the construction is so constructed and located as to be most effective and it operates without materially complicating or adding to the bulk of the structure.

The various objects and features of my invention will be fully understood from the following detailed description of a typical preferred form and application of the invention, throughout which description reference is made to the accompanying drawings, in which:

Fig. 1 is a side elevation of a typical form of structure embodying the present invention showing it applied to a vertically disposed supply pipe. Fig. 2 is an enlarged, perspective view of the counterbalance provided by the present invention with certain parts broken away to show in section. Fig. 3 is an enlarged plan section taken substantially as indicated by line 3—3

on Fig. 1. Fig. 4 is an enlarged detailed vertical sectional view taken substantially as indicated by line 4—4 on Fig. 1. Fig. 5 is an enlarged plan detailed sectional view taken substantially as indicated by line 5—5 on Fig. 1. Fig. 6 is a vertical detailed view showing a part of the structure viewed in the direction indicated by the arrow 6—6 on Fig. 1, and with a portion of the structure in section as indicated by line 6—6 on Fig. 1, and Fig. 7 is a detailed transverse sectional view taken as indicated by line 7—7 on Fig. 5.

The structure provided by the present invention is applicable to a supply pipe A and it involves, generally, a fluid distributing arm, means C coupling the inner end of the arm B to the delivery end of the pipe A, a discharge spout D, means E coupling the spout to the arm B, and counterbalancing means F.

The supply pipe A may, in practice, vary widely in character. However, for purpose of example it may be considered as a rigid or fixed vertically disposed pipe having fluid delivered to it in such manner as to discharge from its upper end. In practice the supply pipe A not only forms the conductor for the fluid handled by the apparatus of the present invention, but it forms the sole support for such apparatus.

The fluid distributing arm B of the structure provided by the present invention may, in practice, vary widely in size, form and character. In the preferred form of the invention the arm is a straight, rigid, tubular element of suitable length and its ends are finished or adapted for connection with the means C and E. In practice the arm B may be formed of a simple length of tubing or pipe and in most cases it is most advantageous to make the arm straight as shown in the drawings.

The means C couples the arm B with the pipe A for universal movement of the arm relative to the pipe. In the preferred form of the invention the means C involves three tubular sections joined end to end by anti-friction means permitting the sections to rotate relative to each other. As shown in the drawings, the means C involves a base section 10 applied to the upper end of the supply pipe A, a head section 11 applied to the inner end of the arm B, and a neck section 12 joining or extending between the sections 10 and 11.

The base section 10 of the means C is shown as a simple or straight tubular part internally threaded at its lower end to receive the threaded upper end of the supply pipe A so that the means

C is joined to the pipe A by a threaded connection 13.

The neck section of the means C is an L-shaped tubular part having an inner end portion 14 forming a socket receiving the pin-like upper end portion 15 of section 10. The outer end portion 16 of section 12 is at right angles to the inner end portion 14 and is shown as a socket receiving a part of the head section 11.

The head section is an L-shaped tubular part 10 the inner end portion 17 of which is in the nature of a pin or male part entering the socket 16. The outer end portion 18 of the head section 11 is at right angles to the part 16 and is internally threaded to receive the threaded inner end of arm B so that the means C is joined to the arms B by a threaded connection 19.

The means C includes anti-friction coupling means 20 joining sections 10 and 12 and anti-friction coupling means 21 joining sections 11 and 12.

The means 20 coupling sections 10 and 12 includes rows of balls 23 in registering grooves 24 in the parts 14 and 15. The balls are introduced into position through a suitable opening 25 normally closed by a plug 26. Through the construction just described the balls couple the neck section 12 with the base section 10 for free relative rotation between the sections and yet the sections are effectively held together against separation. In practice it is desirable to provide sealing means or packing 27 between the sections 10 and 12 to prevent leakage of fluid between them. The means 21 involves rows of balls 28 in registering grooves 29 in the parts 16 and 17. The balls are introduced into place through an opening normally closed by a plug 31. A suitable packing ring 32 is preferably provided to prevent leakage between the parts 16 and 17.

With the means C constructed of sections pivotally connected in the manner just described it serves to join the arm B with the pipe A so that the arm is free to turn about the vertical axis of the pipe and is also free to swing about a horizontal axis which is normal to the vertical axis of the pipe. Through these pivotal axes the arm can be swung to face in any desired direction from the pipe A and can be tilted to extend at any desired angle from the pipe relative to a horizontal plane.

The means E universally couples the spout D with the arm B. The spout D may, in practice, vary widely in form and construction. However, ordinarily it is desirable that it be a simple straight rigid element such as is shown in the drawings and in the particular case illustrated the spout is open at its outer or discharge end 35 and has its inner end coupled to the means E.

The means E preferably involves four tubular sections and anti-friction means coupling the sections for relative rotation. The particular form of the invention illustrated involves a base section 36 applied to the outer end of arm B, a head section 37, a spout section 38 joined to the spout D and coupled to the section 37, and a neck section 39 connecting sections 37 and 36.

The base section 36 is shown as a simple straight tubular part internally threaded at its inner end to receive the threaded outer end of arm B so that the means C is coupled to the arm by a threaded connection 40.

The neck section 39 of means E is an L-shaped tubular element with an inner end part 42 in the form of a socket receiving the outer end portion 43 of section 36. The outer end portion 75

44 of neck section 39 is at right angles to part 42 and is in the nature of a socket receiving the pin-like inner end portion 45 of section 31. The head section 31 in this form of the invention is an L-shaped tubular part with its inner end in the form of the pin entered in the socket portion 44 of section 39. The outer end part 46 of section 37 is at right angles to part 45 and is in the nature of a socket receiving the inner end portion 47 of the spout section 38.

The spout section 38 is preferably a simple, tubular part with its inner end portion 47 received in the socket part 46 of section 37 while its outer end portion 48 is internally threaded receiving the threaded inner end of spout D so that the spout and means E are joined by a threaded connection 49.

Anti-friction coupling means 50 joins sections 36 and 39 of means E while anti-friction coupling means 51 joins sections 31 and 39 of means E while anti-friction means 52 joins sections 37 and 38 of means E.

The several anti-friction coupling means just referred to may be alike in form and construction, in which case each involves rows of balls 60 in registering grooves 61 in the connected parts and the outermost part has an opening 62 through which the balls are arranged in place and the opening 62 is normally closed by a plug 63. Further, it is to be understood that adjoining sections of the means E may be packed or sealed against leakage by means of packing or sealing rings 65.

The counterbalancing means E provided by the present invention involves, generally, a stem 70 coupled to the means C by a suitably connecting means 71, a weight W and means 72 adjustably setting the weight on the stem 70.

The stem 70 is preferably a straight, rigid rod or bar having a shank portion 75 and an extension 76 on which the weight W is carried. The means 71 coupling the stem and means C involves a threaded end 77 on the shank 75 engaged in a socket 78 provided in a boss 79 formed on the head section 11 of means C. In accordance with the preferred arrangement the boss 79 is integrally formed on the exterior of head section 11 so that the socket 78 is concentric with the arm B carried by the head section 11. From Figs. 1 and 3 of the drawings it will be observed that the means 71 coupled the stem 70 with the head section 11 so that the stem projects from the head in a direction opposite to that in which the arm B projects from the head section.

The extension 76 of the stem is preferably polygonal in cross sectional configuration and, in practice, may be an integral continuation of the shank part 75.

The weight W in accordance with the present invention is a sectional structure or element and in the preferred form illustrated it involves a plurality of like disc-shaped sections, each provided with a central stem receiving opening 80. The openings 80 in the sections of the seat are preferably made to slidably receive the extension 76 of the stem so that the weight sections can be moved to any desired position along the stem section or portion 76. The means 72 adjustably setting the weight on the stem preferably involves collars 82 on the stem extension 76 and set screws 83 carried by the collars and engaging the stem to set the collars against axial movement thereon. In the preferred arrangement there are two collars, one at the inner end of the weight and the other at the outer end of

the weight. When the weight sections have been located at the desired point along the stem section 76 the collars 82 are arranged immediately adjacent the end weight sections and the set screws 83 are made tight thus setting the weight in fixed position on the stem.

From the foregoing description it will be apparent that the present invention provides a spout D universally coupled to the supply pipe A so that it can be moved in any desired direction throughout a very wide range. It is to be observed that through the construction provided by the present invention the desired movement of the spout is gained with a minimum number of parts and the parts provided by the present invention are simple, compact, freely working parts which make the structure highly desirable in practice.

It is to be observed that through the present invention the weight of the arm, the means E and the spout D may be accurately counterbalanced by suitable location of the weight W on the stem 70 and when the structure is properly adjusted the spout D, even though the arm may be long and the parts heavy or of sturdy construction, may be easily moved to any position throughout its range of movement.

Having described only a typical preferred form and application of my invention, I do not wish to be limited or restricted to the specific details herein set forth, but wish to reserve to myself any variations or modifications that may appear to those skilled in the art and fall within the scope of the following claims:

Having described my invention, I claim:

1. A fluid distributor applicable to a supply pipe including, an elongate tubular arm, means for coupling the inner end of the arm to the pipe for universal movement of the arm relative to the pipe including, a first L-section with one end for rotatable connection with the pipe and a second L-section having one end rotatably car-

ried by the other end of the first section, the arm being rotatably carried by the other end of the second section and projecting therefrom, a stem attached to the exterior of the second section concentric with the arm and projecting from the said second section oppositely of the arm, and a weight on the stem.

2. A fluid distributor applicable to a supply pipe including, an elongate tubular arm, means for coupling the inner end of the arm to the pipe for universal movement of the arm relative to the pipe including, a first L-section with one end for rotatable connection with the pipe and a second L-section having one end rotatably carried by the other end of the first section, the arm being rotatably carried by the other end of the second section and projecting therefrom coaxially therewith, a stem rigidly supported on the exterior of the second section coaxially of the arm and projecting from the said second section oppositely of the arm, and a weight on the arm, the support of the arm, the stem, the weight and the second section being solely through the engagement of the first mentioned end of the said second section with the first mentioned section.

DOYLE C. WARREN.
